(57) **CLAIM**

The ornamental design for a golf putter head, as shown and described.

DESCRIPTION

FIG. 1 is a perspective view of a golf putter head showing an embodiment of my new design;

FIG. 2 is a front elevation thereof;

FIG. 3 is a rear elevation thereof;

FIG. 4 is a right side elevation thereof;

FIG. 5 is a left side elevation thereof; and,

FIG. 6 is a top plan view thereof.

The broken lines in the drawings are for illustration only, and do not form a part of the claimed design.
